UNITED STATES PATENT OFFICE

JOHN M. STRAND, OF MONMOUTH, ILLINOIS, ASSIGNOR TO WESTERN STONEWARE COMPANY, A CORPORATION OF MAINE

TRIMMER FOR POTTERY-MAKING MACHINES

Application filed August 27, 1928. Serial No. 302,171.

This invention relates to a trimmer for use with pottery making machines.

Molding machines are employed for quantity production of articles of pottery, such as flower pots, and the like, made from clay. The machines in use in the present time include a mold or fixed female die into which the mass of plastic material is placed and a spinning core or male die movable axially into the mold to form the pot by spinning. It inevitably happens that a fin is formed on the finished pot caused by clay being expressed between the top of the fixed die and the core.

The fins so formed are at the present time trimmed by hand which is an expensive and slow method.

An object of my invention is to provide a trimmer for pottery associated with a pottery making machine.

Another object is to provide a trimmer for pottery making machines associated with the spinning die and effective after the die has formed a pot and is being removed from the pot for trimming the fin.

A further object of the invention is to provide a trimmer which automatically trims a pot while the spinning die is being removed from the same.

A further object of the invention is to provide a trimmer which may be readily applied to machines now in use.

A further object of the invention is to provide a trimmer by which the fin is removed by wiping rather than by cutting.

A still further object of the invention is to provide an automatic trimmer for pottery machines.

A yet further object of the invention is to provide a trimmer for pottery machines which is economical to manufacture, easy to apply and efficient in use.

The above, other and further objects will be apparent from the following description, accompanying drawings and appended claims.

According to the invention, a collar is carried by the spinning die to rotate with the same and is axially movable with respect to the die. A plurality of cylindrical pins are vertically carried by the collar for wiping the

fin off the pot as the spinning die is released from the molded pot and is being raised from the same. The means securing the pins in the collar serve also as keys for preventing rotation of the collar on the spinning die.

One embodiment of the invention is illustrated in the accompanying drawings and the views thereof are as follows:

Figure 1 is a side elevational view of a pottery molding machine provided with a trimmer embodying my invention.

Figure 2 is an enlarged fragmental plan view of the spinning die and female die, with the trimmer of my invention on the spinning die.

Figure 3 is a horizontal section on line III—III of Figure 4.

Figure 4 is an enlarged vertical section through the spinning die, the female die, the trimmer and a pot formed by said dies.

Figure 5 is a horizontal section on line V—V of Figure 4.

Figure 6 is a fragmental view partially in section and partially in plan, showing the manner of wiping the fin from a pot by means of the trimmer of my invention.

Figure 7 is an enlarged fragmental vertical section showing the relation between the fixed die, the spinning die, a finished pot and one of the wiping elements of my trimmer.

The form of the invention illustrated in the accompanying drawings comprises a molding machine having a frame 1, base 2, an axially movable rotating spindle 3 driven through gears 4 and 5 from a shaft 6 carried in the frame of the machine. The spindle 3 is raised and lowered by means of a lever 7 connected by means of a gear not shown, with a rack 8 on an enlargement 9 of said spindle.

The frame has a platform 10 to which is secured the fixed or female mold 11 by means of bolts not shown, passing through openings 12 in the flange 13 of said mold.

The spindle 3 carries at its lower end a core shaped to provide the finished form to the interior of the pot molded by the machine.

Figure 4 shows a fixed or female mold 11, the core 14 having a head 15 which is oper-

atively associated with the spindle so as to be rotated and moved axially with the same.

The core has an end 17 carried on guide pins 18 entering recesses 19 and urged outwardly by a spring 20 surrounding a bolt 21 in the head of the core. This arrangement of the core is provided to release the finished molded pot A from the core when the same is moved upwardly out of the pot.

10 A ball of clay or other plastic material is placed in the fixed or female die 11 when the core 14 is raised therefrom. The machine is then actuated to rotate the spindle 3 and with it the core 14 and is moved downwardly by manipulation of the handle 7, being lowered gradually so as to form the clay into the finished form of the pot A.

15 Suitable air holes 22 are provided in the fixed mold 11 while the surface of the core is provided with grooves 23 for the release of air between the pot and the core.

20 The core carries a ring 24, the under margin of which is curved at 25 to shape the upper edge of the pot A.

25 Clay is expressed between the top margin of the fixed mold 11 and the ring 24 as the pot is being formed and it is to the removal of this expressed material which otherwise forms a fin about the pot that my invention is directed.

30 A collar 26 is arranged about the ring 24 of the core so as to have limited axial movement with respect to the core.

35 Radial arms 27 are secured by machine screws 28 to the core at intervals about the same, three of such arms being shown in the drawings. The arms 27 carry downwardly projecting studs 29 which enter counterbore recesses 30 in the collar 26. Springs 31 surround these studs so as to urge the collar 26 downwardly from the arms 27.

40 Headless bolts 32 pass horizontally through spaced apertures 33 in the collar 26, which bolts carry at the inner ends vertically disposed cylindrical pins 34, which pins are case hardened.

45 Nuts 35 fasten the bolts 33 in the collar 26, with the pins 34 clamped against the inner surface of the collar.

50 The ring 24 is provided with vertically disposed recesses 36 in which the ends of the bolts 32 move, thus forming keyways in the core for the bolts and preventing relative rotation between the collar 26 and the core 14. The lower ends of the recesses 36 are curved outwardly as at 37 so as to limit the downward movement of the collar 26 on the core 14.

55 When the core 14 is moved downwardly into the mold 11 in which is the ball of clay to be formed, the lower ends of the pins 34 rest on the upper margin 38 of the mold 11 and ride thereon as the collar 26 is rotated, with the spindle 14 being retained thereagainst by the springs 31.

60 Due to the fact that the fit between the lower surface of the ring 24 and the upper

surface 38 of the mold is a close fit, the clay expressed therefrom is formed as a thin fin about the upper margin of the pot A, and some trimming is accomplished before the core is removed.

65 It is essential to effect trimming by my trimmer that the pot A be released from the spinning core 14.

70 When a pot A has been molded, the lever 7 is actuated to raise the spindle 3 and its attached core 14. The first effect of such movement is to cause separation of the end member 17 of the core from the body of the core, which is a slight separation but sufficient to release the pot from the core. The moment the pot is released from the core, it adheres to the fixed die 11 and is held thereby while the pins 34 on the trimmer wipe off the fin formed about the margin of the pot. The lengths of the pins 34 are such and the arrangement of the collar 26 on the core 14 is such that the ends of the pins remain in contact with the upper margin 38 of the fixed mold 11 until the core is raised a slight distance out of the mold. It is during this time, that is while the core is being raised, that the pins 34 wipe off the fin in the manner shown in Figure 6 and Figure 7 of the drawings. A fin trimmed with this trimmer leaves the pot with a smooth, clean margin.

75 80 85 90 95 100 105 110 115 120 125 130

The recess 25 formed in the lower margin of the ring 24 is concave to produce a convex margin on the pot A. However, the shape of this recess may be other than concave to provide any desirable margin wanted.

110 115 120 125 130

While I have described more or less precisely the details of construction of my invention, yet I do not wish to be understood as limiting myself thereto as I am aware that changes may be made in the arrangement and proportion of parts and that equivalents may be substituted, all without departing from the spirit and scope of my invention.

I claim as my invention:

1. A pottery making machine comprising a fixed mold, a rotatable core, an axially movable collar on said core, and a plurality of vertically arranged cylindrical pins supported by said collar for trimming excess material expressed between said mold and said core.

2. A pottery making machine comprising a fixed mold, a rotatable core, an axially movable collar on said core, and a plurality of vertically arranged cylindrical pins supported by said collar for trimming excess material expressed between said mold and said core, and means for maintaining said pins in position for trimming said excess material after the core is released from the molded pot.

3. A pottery making machine comprising a fixed mold, a rotatable core, an axially movable collar on said core, a plurality of vertically arranged cylindrical pins supported by

5 said collar for trimming excess material expressed between said mold and said core, and means for removably supporting said pins in said collar, said means also cooperating with said core to prevent relative rotation of said collar with respect to the core.

10 4. A pottery molding machine having a spinning core and a fixed mold, a trimmer for removing the fin formed on a pot on said machine in molding, said trimmer comprising a collar on the core axially movable with respect to the same, a plurality of cylindrical pins carried by said collar, springs for urging said collar toward the end of said core, said pins resting on said mold when said core is in forming position and maintained thereagainst by said springs as said core is released from the formed pot for trimming the fin on said pot as said core is 20 being removed from the pot.

25 5. A pottery molding machine comprising a rotatable core and a non-rotatable mold, a trimmer carried by said core, said trimmer comprising a collar axially movable on said core, a plurality of vertically disposed pins carried by said collar arranged to rest on said mold when said core is in forming position, and yieldable means for maintaining said pins against said mold after the core has 30 been released from the molded pot to trim off the fin formed on said pot by the molding operation.

35 6. A pottery molding machine comprising a rotatable core and a non-rotatable mold, a trimmer carried by said core, said trimmer comprising a collar axially movable on said core, a plurality of vertically disposed pins carried by said collar arranged to rest on said mold when said core is in forming position, 40 and yieldable means for maintaining said pins against said mold after the core has been released from the molded pot to trim off the fin formed on said pot by the molding operation, said collar having a plurality of 45 radially arranged headless bolts, said pins being carried in the heads of said bolts against the inside of said collar, means for movably securing said bolts in said collar, said core having a plurality of longitudinal 50 grooves for receiving the inner ends of said bolts to prevent rotation of said collar on said core, arms secured to said core and having studs projecting into said collar, said yieldable means being associated with said 55 studs for urging the collar towards the end of the core.

60 7. A pottery molding machine having a rotatable core and a fixed mold, a trimmer on said core, said trimmer comprising a collar rotatable with said core and movable axially with respect to the same, a vertical pin in said collar disposed to rest on the upper margin of the fixed mold when said core is in forming position, and means cooperating with 65 said collar and said core to maintain said

pin against said fixed mold while said core is being raised from said mold whereby said pin removes the fin formed on a pot by the molding operation after said core is released from the pot.

70 8. A pottery molding machine having a spinning core and a fixed mold for forming pots, a collar axially movably associated with said core, and a trimmer including a vertically disposed rod carried by said collar for trimming the fin from a pot after said core has been released from the formed pot.

75 9. A pottery molding machine having a spinning core and a fixed mold for forming pots, a collar axially movably associated with said core, and a trimmer carried by said collar for trimming the fin from a pot after said core has been released from the formed pot, said trimmer comprising a plurality of vertically disposed pins mounted on said core in a manner to move axially with respect to the same, together with means for maintaining said pins in trimming position as said core is released from a pot.

80 10. A pottery forming machine including two relatively movable pot forming members, a collar supported on one of said members and axially movable with respect to the same, and a pin carried by said collar for trimming purposes.

In testimony whereof I have hereunto subscribed my name at Monmouth, Warren County, Illinois.
